UNITED STATES PATENT OFFICE.

ELBRIDGE J. STEELE, OF NEW HAVEN, CONNECTICUT, ASSIGNOR TO
SARGENT & CO., OF SAME PLACE.

DESIGN FOR A PAPER-FILE.

Specification forming part of Design No. 6,583, dated April 8, 1873; application filed March 12, 1873.

To all whom it may concern:

Be it known that I, ELBRIDGE J. STEELE, of New Haven, in the county of New Haven and State of Connecticut, have invented a new Design for Paper-File; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for the base of that class of paper-files which have a pointed wire extending up from a base; and the invention consists in the peculiar config-

uration and ornamentation of base, as shown in the accompanying illustration.

The base A is of polygonal form. As here represented, there are six sides, the sides inclined upward to a center of corresponding form, each side representing a panel of trapezoidal form filled with tracery, and the top panels of triangular form, as shown in the accompanying illustration.

I claim as my invention—

The design for paper-file, as herein described, and shown in the accompanying drawing.

ELBRIDGE J. STEELE.
